UNITED STATES PATENT OFFICE.

LOUIS SCRIBA, OF MENDOTA, ILLINOIS.

STEAM-BOILER BLOW-OUT OR CLEANER.

No. 831,192.

Specification of Letters Patent.

Patented Sept. 18, 1906.

Application filed February 20, 1906. Serial No. 302,041.

To all whom it may concern:

Be it known that I, LOUIS SCRIBA, a citizen of the United States, residing at Mendota, county of LaSalle and State of Illinois, have 5 invented certain new and useful Improvements in Steam-Boiler Blow-Outs or Cleaners, of which the following is a specification.

My invention relates to steam-boiler blow-outs or cleaners.

10 The object of the present invention is the provision of a simple, durable, and inexpensive device adapted to be positioned within the water-legs surrounding the fire-box of a steam-boiler of a traction, stationary, or locomotive engine and utilized to blow out the 15 sediment under the steam-pressure.

The invention contemplates the provision of an improved device of the character set forth, as will fully appear from the following 20 description, while the novel features of the invention are set forth in the appended claims.

In the accompanying drawings, Figure 1 is 25 a perspective view showing how the invention may be applied to a boiler; Fig. 2, an enlarged horizontal section on line 2 2 of Fig. 1; Fig. 3, a cross-section on line 3 3 of Fig. 2; Fig. 4, a perspective detail of the complete invention; Fig. 5, a detail of the inner or rotatable tube; Fig. 6, a longitudinal section of Fig. 4, and Fig. 7 a detail section on line 7 7 of Fig. 4.

An ordinary boiler, such as might be used 30 for a traction, stationary, or locomotive engine, is shown at 1. The present invention is located in the lower part of the water-legs 2, surrounding the fire-box 3, as the sediment in the steam-boiler collects at these 35 points.

40 The numerals 4 designate outer tubes disposed horizontally at the bottoms of the four water-legs 2, said tubes having elongated or more or less elliptical openings 5 in their tops, and they are rigidly secured in position by 45 being screwed through the walls of the fire-box, and on their outer ends are screwed caps 6, which are provided with blow-off cocks 7. Integral with or connected to the upper faces of the tubes 4 and resting against 50 or connected to the walls of the water-legs are deflecting flanges or members 8, whereby the sediment is caused to gravitate through the openings 5.

55 Located within and snugly fitting the outer tubes 4 are the inner revoluble tubes 9, which

are provided with openings 10, corresponding to the openings 5 and adapted to register therewith. The inner tubes 9 also have blow-out holes or openings 11, which may be brought into alinement with the blow-off 60 cock 7 when the inner tubes are turned or reversed from their normal position; but when in normal position the opening 11 of each tube 9 is closed by the cap 6. The inner tubes 9 have turn-handles 12 secured 65 thereto which pass through the caps 6.

The ends 13 and 14 of the outer and inner tubes are open, so that the water is in constant communication with the interiors of the tubes 9. All of the joints may be suit- 70 ably packed.

Ordinarily the inner tubes 9 are positioned with the openings 10 uppermost and in register with the openings 5, so that the blow-off ports 11 are closed, although the water has access to the interiors of the tubes 9. When in this position, the sediment passes through the openings 5 and 10 and accumulates in the interior of the tubes 9; but when it is desired to blow out the accumulations the engineer 80 or fireman turns the handles 12 until the ports 11 are in register with the respective blow-off cocks 7. Any suitable means may be employed for limiting this turning action. When the tubes 9 or such tube as may be 85 turned become reversed, the water under the pressure of the steam blows out the accumulations within the pipes 9 through the blow-out cocks 7, assuming that the latter have been opened. After the sediment has 90 been eliminated the tubes 9 are turned back to their former position and the blow-out cocks 7 closed.

Having thus described my invention, what I claim as new, and desire to secure by Letters Patent, is—

1. In a steam-boiler blow-out or cleaner, the combination with an outer tube having an opening for the elimination of the sediment from said tube and also open for the 100 passage of the sediment to its interior, of an inner movable tube located within the outer tube aforesaid and open to receive the sediment within itself and also provided with a voiding-opening which may be brought into 105 communication with the elimination-opening of the outer tube by moving said inner tube.

2. In a steam-boiler blow-out or cleaner, the combination with an outer tube having an opening for the elimination of the sedi- 110

- ment from said tube and also open for the passage of the sediment to its interior, of an inner rotary tube located within the outer tube aforesaid and open to receive the sediment within itself and also provided with a voiding-opening which may be brought into communication with the elimination-opening of the outer tube by turning said inner tube.
- 10 3. In a steam-boiler blow-out or cleaner, the combination with an outer tube having an opening for the elimination of the sediment from said tube and also provided with openings for the reception of the sediment, of 15 an inner movable tube located within the outer tube and having openings normally registering with the sediment-receiving openings in the outer tube and also provided with a voiding-opening, said inner tube being 20 adapted for movement to throw its openings out of register with those of the outer tube and to place its voiding-opening in communication with the elimination-opening of the outer tube.
- 25 4. In a steam-boiler blow-out or cleaner, the combination with an outer tube having an opening for the elimination of the sediment from said tube and also provided with openings for the reception of the sediment, of 30 an inner rotatable tube located within the outer tube and having openings normally registering with the sediment-receiving openings in the outer tube and also provided with a voiding-opening, said inner tube being 35 adapted for rotation to throw its openings out of register with those of the outer tube and to place the voiding-opening in communication with the elimination-opening of the outer tube.
- 40 5. In a steam-boiler blow-out or cleaner, the combination with an outer tube having an opening for the elimination of the sediment and open for the passage of the sediment to its interior, of a sediment-deflector for deflecting the sediment to the receiving-opening of the outer tube, and an inner movable tube located within the outer tube aforesaid and open to receive the sediment within 45 itself and provided with a voiding-opening which may be brought into communication
- with the elimination-opening of the outer tube by moving said inner tube.
6. In a steam-boiler blow-out or cleaner, the combination with an outer tube having an opening for the elimination of the sediment and open for the passage of the sediment to its interior, of a sediment-deflector comprising members which converge toward said outer tube to direct the sediment to the sediment-receiving opening thereof, and an inner movable tube located within the outer tube aforesaid and open to receive the sediment within itself and provided with a voiding-opening which may be brought into communication with the elimination-opening of the outer tube by moving said inner tube.
7. In a steam-boiler blow-out or cleaner, the combination with a water-leg of the firebox, of an outer tube disposed in the lower portion of the water-leg and having a sediment-receiving opening and also a sediment-elimination opening, and an inner movable tube located within the outer tube aforesaid and provided with a voiding-opening which may be brought into communication with the elimination-opening of the outer tube by moving said inner tube.
8. In a steam-boiler blow-out or cleaner, the combination with a water-leg of the firebox, of an outer tube disposed in the lower portion of the water-leg and having a sediment-receiving opening and a sediment-elimination opening, an inner movable tube located within the outer tube aforesaid and provided with a voiding-opening which may be brought into communication with the elimination-opening of the outer tube by moving said inner tube, and a sediment-deflector comprising members converging from the walls of the water-leg toward the outer tube and adapted to direct the sediment to the sediment-receiving opening of said outer tube.

In testimony whereof I hereunto affix my signature in presence of two witnesses.

LOUIS SCRIBA.
